UNITED STATES PATENT OFFICE

2,470,250

BELT CARRIED TAPE HOLDER FOR
ELECTRICAL WORKERS

David Kienle, New York, N. Y.

Application February 6, 1946, Serial No. 645,788

1 Claim. (Cl. 242—55.4)

1

This invention relates to an improved tape holder for electrical workers, and one of the objects of the invention is the provision of a holder for tape, which can be attached to a garment belt, and which will enable the worker to pull a section from a reel of tape and sever it from the body of the reel or roll, so that he may be able to obtain a piece of tape without delay and without using special tools.

Another object of the invention is to provide a tape roll holder, in which more than one roll of tape may be supported, so that the workman may have available adhesive friction tape and rubber tape.

A still further object of the invention is the provision of a tape holder with a cut off knife which may be adjusted to cutting position, or clamped in non-cutting position, and to provide a spring yielding guard for this cutting knife, which will yield when a tape to be cut is pressed against the guard.

With the above and other objects in view, the invention comprises certain new and useful constructions, combinations and arrangements of parts, clearly described in the following specifications and fully illustrated in the drawings, in which:

Fig. 1 is a side view, showing the knife guard in raised position.

Fig. 2 is a similar view, showing the knife guard in lowered position, so that tape may be severed.

Fig. 3 is a top plan view, showing a holder provided with four parallel tape rolls.

Fig. 4 is a side view thereof.

Fig. 5 is a detail bottom plan view of the base plate which supports the adjustable cutting knife carrier.

Referring to the drawings, 5 designates a main frame plate, which is formed with rearwardly disposed flanges 6 and 7 at the ends of the plate. Each flange is provided with a slot 8, through which the body or garment belt 9 is extended, so that the plate may be strapped to the body of the workman.

A wooden shaft 10 is secured to one side of the plate 5 by means of the screw or connector 11, and on this shaft a plurality of tape rolls 12, 13, 14 and 15 may be mounted, disc washers 16 being arranged between the adjacent sides of these rolls. A washer disc 17 is arranged adjacent the outermost roll and a cotter pin 18 is extended through the rounded outer end portion of the shaft 10, to hold all of the rolls on the shaft.

To one side of shaft 10 a plate 19 is attached

5 to the frame plate 5, by welding or otherwise. This plate is formed with a slot 19a through which screw 20 extends. The head of this screw is attached to the blade carrier plate 21, on which the razor or cutting blade 22 is secured, as by means of the screws 23 and 24. The cutting blade and its plate carrier 21 are adjusted by means of the screw 20, and the nut 25, so that the cutting edge of the blade 22 may be clamped forwardly of the base or holding plate 19, or rearwardly thereof.

Above the cutting knife a U-shaped metal guard 26 is pivoted upon the stud shaft 27, and is normally held in an upper position by means of the 15 spring arm 28, which extends from the spring coil 28a, secured on the post or screw 29, which is attached to the frame plate 5.

Side flanges 26a of the U-shaped guard 26 are 20 arranged to swing downwardly along the outer edges of the plate 19, and the longitudinal edge of the guard to swing downwardly over the cutting blade, as shown in Fig. 2, under the pulling pressure applied on the end of the tape, and by 25 pressing the tape against the cutting edge, which has been clamped in cutting position, by operating the nut 25, the tape may be severed.

Immediately over the guard 26 a lever 30 is pivoted on the frame plate 5, by means of rivet 31, and on this lever or arm, presser feet 32, each 30 of spring construction, are mounted, so that they will engage the tape from one of the rolls. The lever or arm 30 may be swung upwardly, so that its presser feet will be out of the path of the tapes, and a fresh roll may be inserted in the 35 holder.

It will be seen that my invention provides a tape holder, which may be strapped to the belt of the workman, and that one of the rolls may be provided with tape of the adhesive friction or tacky type, and another roll provided with heavy rubber tape, and the other rolls, when more than two rolls are used, may be provided with other types of tape, or used for a reserve supply of the two kinds of tape named.

45 A radio worker, electrician, or repairman, may work continuously, without looking for tape, and without applying more than one hand to the pulling and cutting of the tape, and will therefore do better and more work.

50 Having described the invention it is understood that various changes in the details of construction, their combination and arrangement may be resorted to, within the scope of the invention, as defined by the claim hereof.

I claim as new and patentable:

An electrical tape holder comprising a main frame plate adapted to be connected to a strap, a stub shaft connected to the plate and extending laterally therefrom and adapted to support rolls of electric tape, means removably connected to the stub shaft to prevent the displacement of the tape rolls therefrom, a member secured to the main frame plate and extending laterally therefrom and parallel to the stub shaft, cutting blade means secured to said member, a second member secured to the main frame plate and extending laterally therefrom above the first member and parallel thereto, a spring biased guard pivoted on the second member and adapted to be extended over the cutting blade means and serve as a support for the tape strips which have been freed from the rolls, a lever pivoted upon the main frame plate and having a portion extending laterally above the tape strips and over the guard, pressure feet secured to said portion and engaging with the tape strips and guard to

hold the tape strips upon the guard, said lever with the pressure feet being adapted to be elevated out of the path of the tape to permit the insertion of new rolls of tape.

DAVID KIENLE.
